UNITED STATES PATENT OFFICE.

JAMES H. LEPPER, OF BANGOR, MICHIGAN.

DISPLAY RACK.

Application filed March 28, 1927. Serial No. 178,698.

This invention relates to certain novel improvements in display racks and more particularly to a rack for supporting material sold in rolls and has for its principal object 5 the provision of an improved construction of this character which will be highly efficient in use and economical in manufacture.

Among the salient objects of the invention is to provide a display rack from which material sold in rolls may be supported and measured and cut in the desired length to be sold.

Other objects will appear hereinafter.

The invention consists in the novel combination and arrangement of parts to be hereinafter described and claimed.

The invention will be best understood by reference to the accompanying drawings, showing the preferred form of construction 20 and in which:

Fig. 1 is a typical side elevational view of the invention;

Fig. 2 is a sectional detail view taken substantially on line 2—2 of Fig. 1;

Fig. 3 is an enlarged fragmentary sectional detail view taken substantially on line 3—3 of Fig. 1; and

Fig. 4 is a perspective view of a cutting blade embodied in the invention.

30 The preferred form of construction, as illustrated in the drawing, includes a rack comprising a bottom plate 10 supported by suitable feet 11. Extending upwardly from this bottom plate at opposite ends thereof, are end plates 12 reenforced in their vertical position through the medium of bracing bars 13. Secured to the end plates, a substantial distance from the top edges 14 thereof is a top plate 15. This top plate 15 comprises 35 two sections 16 and 17 secured together by suitable screw elements 18. Secured to the end plates between the section 17 and bottom 10 are a plurality of equally spaced brackets 19 which are adapted to removably support a 40 roll of material (not shown). These brackets include lateral shelves 20 substantially semi-circular in cross section and on these shelves is placed the ends of the rod of the roll of material. These brackets 20 are secured to the end plates in parallel rows 45 through the medium of screw elements 21.

The upper end portions 22 of the end plates have secured thereto brackets 23, said brackets 23 being located above the section 50 16 and formed substantially similar to the brackets 20.

The longitudinal marginal edge portions 24 of the section 16 has formed therein longitudinally extending L-shaped grooves 25 with the horizontal portion of the grooves opening from the longitudinal edges 24.

Slidably arranged in these grooves are cutter frames 26. These cutter frames include top plates 27 having spaced perforations 28 formed therein and carried by the top plates 65 are pins 29 which work in the horizontal portions of the grooves. The frames further include bottom plates 30 which have formed thereon studs 31 adapted for insertion in the perforations 28, said bottom plates being secured to the top plates by suitable screw elements 32. Between the top and bottom plates of the cutter frames is adapted to be arranged razor blades 33 which have perforations 34 formed therein through which the 70 screws 32 and studs 31 project, the cutting edges 35 of the razor blades being exposed from the side edges of the cutter frames and the inner portions of these razor blades extending into the horizontal grooves. The 75 top plates further include handles 36 which facilitate moving the cutter frames longitudinally of the section 16.

Secured to the end plates 12 on opposite side edges thereof are blocks 37. Formed in these blocks 37 are inwardly and upwardly extending grooves 38 which terminate into end portions of grooves 39 formed in the longitudinal edges of the section 17.

Clamping rods 40 have their end portions 90 mounted in the grooves 38 and these clamping rods are adapted to be moved toward the longitudinal edges of the section 17 for confinement in the longitudinal grooves 39. In use, the rolls of material to be displayed are 95 supported by the brackets 19. To cut a length of material from one of the rolls the roll is removed from the brackets 19 supporting the same and mounted with the end portions of its rod in the brackets 23. The material is rolled out in a direction between the section 16 and clamping rod 40 in the direction of the unrolling of the material. The length to be cut from the roll is measured through the medium of measuring 100 marks 41 stamped or printed on the edges 42 of end plates 12. When the material has 105 been unrolled the required distance the clamping rod adjacent thereto is moved to force a portion of the material into the longitudinal groove adapted to receive that clamping rod. This clamps the material in 110

suspended position for operation upon by the cutter blade adjacent thereto. By moving this cutter blade longitudinally of the section 16 the length of material will be severed from the roll and supported during this cutting operation through the medium of the clamping rod adjacent thereto.

From this it will be seen that I provide a rack and associated parts for supporting a length of material from a roll while being severed.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claims.

Having thus described my invention what I claim as new and desire to protect by Letters Patent is:

1. In a display rack, a frame including end plates and a top plate between the end plates, said top plate having a longitudinal L-shaped groove formed therein, cutter mechanism operable in the horizontal portions of the groove, pins carried by the mechanism and operable in the vertical portion of the groove, and means carried by the end plates for supporting a roll of material to be severed in length by the mechanism when unrolled, said mechanism including two plates, means detachably connecting the plates together, and a cutter blade supported between the plates, and means movable into clamping relation with the unrolled material for supporting the material during cutting operation thereon.

2. In a display rack, a frame including end plates and a top plate between the end plates, said top plate having a longitudinal L-shaped groove formed therein, cutter mechanism operable in the horizontal portions of the groove, pins carried by the mechanism and operable in the vertical portion of the groove, and means carried by the end plates for supporting a roll of material to be severed in length by the mechanism when unrolled, said top plate having a longitudinal groove formed therein, grooved blocks carried by the end plates, the grooves of said blocks opening into the ends of the longitudinal groove and a rod having its end portions mounted in the grooves of the blocks and movable in a direction to clamp the unrolled material in the longitudinal groove.

3. In a display rack, a frame including end plates and a top plate between the end plates, said top plate having a longitudinal L-shaped groove formed therein, cutter mechanism operable in the horizontal portions of the groove, pins carried by the mechanism and operable in the vertical portion of the groove, and brackets carried by the end plates for supporting a roll of material to be severed in length by the mechanism when unrolled, said top plate having a longitudinal groove formed therein, grooved blocks carried by the end plates, the grooves of said blocks opening into the ends of the longitudinal groove and a rod having its end portions mounted in the grooves of the blocks and movable in a direction to clamp the unrolled material in the longitudinal groove.

In testimony whereof I affix my signature.

JAMES H. LEPPER.
